UNITED STATES PATENT OFFICE

ROBERT T. WILLIAMS, OF QUINCY, ILLINOIS, ASSIGNOR TO H. M. SHEER COMPANY,
OF QUINCY, ILLINOIS, A CORPORATION OF ILLINOIS

STOVE

Application filed May 31, 1927. Serial No. 195,473.

This invention relates to an improvement in stoves.

The object of the invention is to provide a stove in the nature of a coal burning stove, or one for burning solid fuel, of an improved construction which will produce an even burning of fuel within a fire-pot without the possibility of the coal caking and sealing up around the edges as it does in the ordinary form of coal stove. The invention is especially designed for use in connection with brooders, although it is not limited especially to this purpose.

The invention consists more especially in the construction of the stove and the many novel features involved and incorporated therein. A humidifying pan is provided upon the stove support and beneath the stove and is provided with openings on all four sides for better diffusion.

The shaker-grate is mounted on ball bearings to facilitate ease in operation thereof, and the construction of the grate allows the removal of clinkers merely by withdrawing the shaker and moving it relative to the grate. A preheated draft intake is arranged at the bottom of the stove to supply air and a draft thereto, and combined with this is a cold air regulator arranged at the top of the stove for admitting cold air thereto. A removable baffle plate extends between the cold air chamber and smoke-stack for forcing the cold air into the combustion area before its escape up the chimney. This baffle plate allows the smoke to be discharged from the center of the stove instead of from its edge, as in the ordinary stoves of this character, which center outlet encourages the fire to burn out in the center of the fire-pot as well as the outside walls, giving a steady heat. The baffle plate is provided with sloping back edges to allow the soot to slide out of the way of the passing smoke.

The interior of the fire-pot is corrugated and a plurality of vertical fins are formed on the exterior of this fire-pot, these fins and corrugations being parallel and corresponding to each other, so that the path of the circulating air is not affected, the air simply passing upward between and for the entire

length of the fins in direct contact therewith, which fins form vertical flues for directing the air in a circulating path up along the surface of the stove, preventing any heat eddies. Both sides of the flanges are equally effective.

When the vertical flanged fire-pot desires to expand, it is perfectly free to do so, and there are no lateral restraints tending to cause a cracking of the fire-pot, as might occur and often would if the fins were arranged circumferentially of the fire-pot. The fire-pot tapers from its bottom to top, and this taper, together with the parallel interior corrugations and outside fins, prevents any sealing over on the inside of the stove by the settling of the coals. The walls are thus made thinner, which decreases the cost of manufacture, and likewise of shipping by reason of the lighter weight of the stove, and on the other hand provides a greater radiation of heat by reason of the thinner walls.

In the accompanying drawings:

Fig. 1 is a vertical sectional view through the complete stove;

Fig. 2 is a top plan view thereof;

Fig. 3 is a plan view of the head and baffle plate removed;

Fig. 4 is a transverse sectional view on the line 4—4 of Fig. 2 through the head;

Fig. 5 is a sectional view on the line 5—5 of Fig. 1;

Fig. 6 is a detail sectional view through one side of the complete stove;

Fig. 7 is a sectional view through the grate and a portion of the base;

Fig. 8 is a plan view of the shaker; and

Fig. 9 is a side elevation of the fire-pot removed.

The stove shown in Fig. 1 is mounted upon a support 1 provided with upstanding lugs 2 upon which is seated the base 3 of the stove, as clearly shown in Fig. 1. The back lugs 2 are connected together by a stop 4 at the back edge of the support 1. A humidifying pan 5 is mounted upon the support 1, its backward movement being limited by a stop 4 extending across the base, as shown in Fig. 1. This humidifying pan 5 is thus mounted immediately beneath the stove, and is open

on all four sides thereof to supply humidity to the atmosphere.

The upper portion of the base 3 has lugs 6 extending inwardly therefrom, as shown in Figs. 5 and 7, which are provided with grooves 7, in which are mounted ball bearings 8. A grate 9 is provided with struck-out portions 10, which are seated upon the ball bearings 8 for supporting the grate. This 10 grate is provided with a central opening 11 and integral lugs 12 extending inwardly toward each other below the grate 9, as shown in Fig. 1, to receive and support a shaker 13. An integral depending lug 14 extends downwardly from the front edge of the grate 9 and when the shaker is in position upon the lugs 12, the lug 14 extends into a longitudinal slot 15 in order to limit sliding movement of the shaker in both directions. Both 20 the grate and the shaker are provided with a plurality of small holes therethrough to allow the ashes to sift down from the body portion of the stove. In order to shake the grate, the shaker 13 is moved back and forth, 25 which gives the grate an oscillatory movement upon the ball bearings 8, causing the ashes to sift down through the openings in the grate and shaker. The shaker 13 is slidably mounted on the lugs 12 and may be 30 pulled out, its outward movement being limited by the lug 14 to allow any clinkers or cinders to drop down through the central hole 11 in the grate 9 and through a notch 16 formed in the end of the shaker 13, as 35 shown in Fig. 8, which notch registers with the central opening 11 to allow the clinkers or cinders to drop from the interior of the stove. This makes it unnecessary to cool off 40 the stove or to remove the grate in order to extract clinkers which may get into it and oft-times hinder the successful operation of the stove.

A rib 17 extends upwardly from the base 3 and a fire-pot 18 fits within the rib 17 and is 45 mounted upon an inturned flange 19 carried by the base, which flange also supports the projections 6 which contain the ball bearings 8 for supporting the grate.

The interior of the fire-pot 18 is corrugated as at 19, as shown in Figs. 1 and 5, and extending parallel with these corrugations 19 are exterior fins 20, which extend vertically along and are integral with the fire-pot 18. These fins form vertical flues along the outer 55 side of the fire-pot, in order to direct the air upward along the stove and, in contact therewith and which produces the greatest possible radiation. The fire-pot is larger at the bottom than at the top with the general tapering to the latter so that the coal burns and settles down through the grate with no possibility of its caking or sealing up air-tight around the edges. This is also facilitated by the corrugated interior. It will be noted 65 especially in Fig. 5 that the corrugations 19

which extend parallel with the fins 20 reduce the amount of material in the walls of the fire-pot to a minimum, thus decreasing the cost of manufacture and likewise of shipping by the decrease in weight and material. 70 These thinner walls also provide greater heat radiation. The thickness of the metal is substantially the same at all points, which lessens the tendency toward cracking of the fire-pot, due to unequal expansion of the metal. 75 The construction of this fire-pot is an important feature of this invention. 80

A head 21 is secured upon and supported by the fire-pot 18 and this head is provided with an inturned flange 22 upon which is seated a baffle plate 23. This baffle plate 23 is removable and seated between the lugs 24, which hold it in its proper position with the head 21. An upstanding flangs 25 co-operates with a depending flange 26 on the top 27, 85 which is seated over the head 20 to divide the back portion of the top into compartments, which communicate with the interior of the fire-pot over the front edge of the removable baffle plate 23. A damper 28 is carried by brackets 29 for regulating the supply of air into the air chamber 30 on one side of the flanges 25 and 26. A smoke chamber 31 is provided on the opposite side of these flanges and is open at its top to allow the discharge of smoke through a suitable pipe connected with the flange 32 formed upon the top 27. A flange 33 is also formed at the front side of the smoke chamber 31 in order to limit the communication of the smoke chamber 100 with the interior of the fire-pot to the center thereof, so as to promote the natural draft through the center of the stove instead of only at its outer edges as in most stoves of this character. 105

The feed door 34 is connected with the top 27 to allow the admission of fuel into the fire pot 18 and this door extends entirely across the top 27 in order that a coal scuttle may be inserted thereinto, thus preventing spilling of any coal as it is admitted to or inserted into the stove as so often happens. 110

A preheated air intake tube 35 is secured to the side of the fire-pot 18 and communicates at its lower end with the opening 36 into the base 3 for preheating the air or draft through the base and the fire-pot for the stove. A draft control 37 regulates the draft through the tube 35 and this draft control 37 is automatically actuated by any suitable form of thermostatic device, designated generally by the numeral 38, as shown in Fig. 6, and is connected with the damper 28 by means of a flexible connecting wire 39, which simultaneously actuates the draft control and damper, 115 opening the one upon the closing of the other. 120

It will thus be seen that a coal stove is provided of an improved construction, which is especially designed for use in connection with chicken brooders, and by reason of its many 130

superior and novel features, it is a great improvement over any of the forms of coal stoves now in use. It is not limited strictly to the burning of coal but any solid fuel may be used in it.

5 I claim:—

1. A stove of the character described including a fire-pot having interior corrugations and outside vertical fins forming flues thereabout extending in an upward direction.

10 2. A stove of the character described including a fire-pot having approximately vertical corrugations formed in the interior surface thereof and having exterior vertical fins formed upon the outer surface thereof and parallel with the interior corrugations to provide the walls of the fire-pot of approximately uniform thickness and to form approximately vertical air flues about the exterior of the 15 fire-pot to increase the radiation of heat therefrom and to conduct the air into contact with approximately the entire exterior surface of the fire-pot.

20 3. A stove of the character described including a fire-pot having approximately vertical corrugations formed on the interior surface thereof.

25 4. A stove of the character described including a fire-pot having the walls thereof tapering approximately from the lower to the upper end thereof, and having upwardly extending corrugations formed in the interior tapering surface thereof.

30 5. A stove of the character described having a fire-pot provided with interior and exterior corrugations extending longitudinally thereof, said corrugations being respectively convex and concave to provide exterior flues about the fire pot, and to prevent caking over 35 of the fuel within the firepot.

40 6. A stove for burning solid fuel having a grate therein, a fire-pot disposed above the grate, and provided with interior corrugations extending downwardly toward the grate, and a fuel opening in the upper portion of the stove near the top of the firepot.

45 7. A stove for burning solid fuel having a grate therein, a firepot having solid walls extending upwardly from the grate and provided with interior longitudinal corrugations in the walls thereof to prevent caking over of the fuel, and a fuel opening for the stove near the top of the fire pot for introducing the fuel into the upper portion of the 50 fire pot.

55 8. A stove for burning solid fuel having a grate therein, a fire pot having solid walls extending upwardly from the grate and inclined inwardly toward the top, said fire pot being provided with interior longitudinally 60 extending corrugations in the walls thereof to prevent bridging over of the fuel, and a fuel opening for the stove near the top of the fire pot for filling the fire pot approximately 65 full of fuel.

9. A fire pot for a solid fuel stove, having solid continuous walls throughout the length thereof and having interior longitudinally extending corrugations in the inner walls thereof to prevent bridging over of the fuel. 70

10. A fire pot for a solid fuel stove having solid continuous walls throughout the length thereof, tapering inward toward at least one end thereof, and having interior corrugations extending lengthwise of the fire pot in the inner walls thereof to prevent bridging over of the fuel. 75

11. A fire pot for a solid fuel stove having walls free from perforation for a fuel opening, and having interior corrugations extending lengthwise of the fire pot to prevent caking over of the fuel. 80

12. The combination of a slow burning stove for burning solid fuel having a fire pot forming the major portion of the body thereof, said fire pot being imperforate in the sides thereof, and a fuel opening near the top of the stove for introducing fuel to the fire pot through the upper end. 85

13. A slow burning stove having a grate, 90 an elongated continuous fire-pot extending upwardly from the grate, and a fuel inlet near the upper end of the fire-pot, the inner walls of said fire-pot being imperforate, and being corrugated longitudinally thereof. 95

14. A slow burning stove having an elongated continuous upwardly extending fire-pot and extending throughout a major portion of the height of the stove, a fuel inlet near the upper end of the fire-pot, said fire-pot being adapted to be filled approximately full of fuel, and having the inner walls thereof imperforate, and upwardly extending corrugations formed in the inner walls of the fire-pot. 100

15. A slow burning stove having an elongated upwardly extending fire-pot in the form of a truncated cone, a grate disposed approximately at the base thereof, and means for admitting fuel to the upper end of said fire-pot, said fire-pot having interior upwardly extending corrugations. 110

16. A stove of the character described comprising an elongated upwardly extending fire-pot approximately in the form of a truncated cone, a grate disposed approximately at the base thereof, said fire-pot being adapted to be filled approximately full of fuel, and means for admitting fuel to the upper end of the fire-pot, said fire-pot having exterior upwardly extending corrugations formed on the inner wall thereof for preventing bridging over of the fuel and carrying off the products of combustion. 115

In testimony whereof I affix my signature 125
ROBERT T. WILLIAMS.
